UNITED STATES PATENT OFFICE.

OTTO THOST, OF ZWICKAU, GERMANY.

DESIGN FOR A GRATE-BAR.

SPECIFICATION forming part of Design No. 30,506, dated April 4, 1899.

Application filed February 25, 1899. Serial No. 706,889. Term of patent 14 years.

To all whom it may concern:

Be it known that I, OTTO THOST, a subject of the King of Saxony, and a resident of Zwickau, in the Kingdom of Saxony, German Empire, have invented and produced a new and original Design for Grate-Bars, of which the following is a specification, reference being had to the accompanying drawings, forming a part thereof.

10 The accompanying drawings represent the design which embodies my invention.

15 The leading feature of my design consists in a grate-bar which comprises a center portion, being formed of squares at the top, with grooves on the side, which are gradually decreasing, ending in a straight bottom edge. On either side the bar has a support, one of which is provided with a lug and a corresponding recess.

20 The drawings illustrate a grate-bar, in which 1 represents the practically square top

surfaces, with the intermediate connecting reduced pieces. 2 is the support, showing the lug 3 and the recess 4, while the support at the other end, Figure 2, shows a triangular 25 projection 5. The lugs and supports are practically rectangular, Figs. 1 and 2, while the main center portion is curved at 6 and gradually diminishes in size from the squares forming the top down to the straight bottom edge, 30 Fig. 3. Two bars laid side by side show the squares to alternate, Fig. 1.

Having thus described my invention, I claim—

15 The design for a grate-bar substantially as 35 shown and described.

In testimony whereof I affix my signature in the presence of two subscribing witnesses.

OTTO THOST. [L. S.]
